UNITED STATES PATENT OFFICE

EDWARD D. DAVIS, OF CHICAGO, ILLINOIS, ASSIGNOR TO THE BOYE NEEDLE COMPANY,
OF CHICAGO, ILLINOIS, A CORPORATION OF ILLINOIS

COMMODITY CABINET

Application filed November 3, 1930. Serial No. 493,122.

This invention relates particularly to cabinets adapted to the purpose of storing and displaying small articles of merchandise; and the primary object is to provide a cabinet 5 of simple and inexpensive construction which is well adapted to this purpose.

In the embodiment of the invention illustrated, the cabinet is adapted for storing and displaying small articles of merchandise, 10 such as safety pins, or any other small articles adapted to be mounted on cards.

The invention is illustrated in its preferred embodiment in the accompanying drawings, in which—

15 Figure 1 represents a perspective view of a commodity-cabinet constructed in accordance with the invention; Fig. 2, a sectional view, the section being taken as indicated at line 2 of Fig. 1; Fig. 3, a sectional view, the section 20 being taken as indicated at line 3 of Fig. 2; Fig. 4, a plan sectional view, the section being taken as indicated at line 4 of Fig. 2; and Fig. 5, a plan view of a merchandise card which is adapted to be stored and displayed 25 in the cabinet.

In the construction illustrated, 1 represents the front wall, 2 the rear wall and 3 the side walls of the cabinet. The side walls 3 are preferably somewhat wedge-shaped as 30 illustrated in Fig. 1 with the rear portion of each wall 3 elevated above the front portion thereof.

As shown more clearly in Fig. 2, the cabinet is provided with two bottom sections 4 and 5 which are separated by a transverse 35 partition 6. Both sections are inclined, section 4 having its front end joined to the lower portion of front wall 1 and its rear end connected to the partition 6 at an intermediate elevation, while the section 5 is connected to the lower portion of partition 6 and to an intermediate portion of the rear wall 2. In the illustration given, the partition 6 is located nearer to the front wall 1 than to the rear wall 2, thus providing a front compartment A which is smaller than the rear compartment B.

The compartment B is divided into a number of smaller compartments by partitions 7, 50 and the front compartment A is divided into

a number of compartments by partitions 8. Any desirable number of partitions, however, may be used in either of the compartments and the partition wall 6 may be so located as to provide compartments of any desired 55 length.

A cross-piece 9 is preferably secured to the cabinet at a point adjacent the front wall 1, and a second cross-piece 10 may be secured to the cabinet along the partition 6. The 60 cross-pieces 9 and 10 are drilled to receive the ends of posts 11, one of which is located in each of the compartments. The lower ends of the posts 11 are received within holes formed in the floor sections 4 and 5. The 65 cross-piece 10 not only serves to hold the posts 11 in position and as a retaining member for merchandise within the compartments B, but also serves as a handle for the cabinet. 70

Display-cabinets of this construction may be furnished by manufacturers of small articles of merchandise to dealers throughout the country; and one purpose of the construction is to provide against improper use 75 of the cabinet and against unauthorized or fraudulent use thereof. Thus, a manufacturer who furnishes the cabinets to dealers gratis, with the understanding that each cabinet shall be used only in displaying and selling merchandise of his manufacture, may supply cards specially adapted for use in the cabinet, and thus may guard against an unauthorized use of the cabinet. For this purpose, it is preferred to use a card 12, such 80 as, for example, is illustrated in Fig. 5. The card is provided at its front side with a slot or recess 13 which is adapted to engage one of the posts 11. The card 12 may carry 85 small articles, such as safety pins, etc. 90

In order to facilitate removal of merchandise cards which are carried in the rather deep compartments and which have their slots or notches 13 in engagement with the posts 11, I prefer to employ the following 95 construction. The rear wall 2 is provided with finger slots or openings 14 which preferably extend to the bottom section 5. Along the top or upper side, the slots 14 are preferably flared or enlarged at 15 so as to per- 100

mit the cards to be more readily grasped at that point between the fingers and thumb. Likewise, the partition 6 is provided with vertical slots 16 which extend substantially to the bottom section 4. Immediately above the slots 16 semi-circular portions of the member 10 are cut away to provide finger openings 17.

In the use of the cabinet, the cards 12, which may be of small size adapted to fit the smaller compartments or of large size adapted to fit the larger compartments, are introduced into the compartments, the posts 11 extending into the recesses 13 of the cards. The inclined floor sections 4 and 5 hold the cards at an angle at which they are clearly visible to the customer who may stand in front of the cabinet. To remove one of the merchandise cards, the customer or dealer, may extend his finger through the slotways 14 and 16 and raise the upper end of the card. When the card has been raised to a point near the top of the wall, it may be grasped between the thumb and fingers and lifted out of the compartment. The flared openings 15 in the rear wall 2 and the cut away portions 17 in the cross-piece 10 enable the customer or dealer to grasp the card with substantially no effort when one end of the card has been raised.

While I have disclosed one means by which the manufacturer may guard against unauthorized use of the cabinet, it is obvious that other means or expedients may be used without departing from the spirit of my invention.

The foregoing detailed description has been given for clearness of understanding only and no unnecessary limitations should be understood therefrom, but the appended claims should be construed as broadly as permissible in view of the prior art.

I claim:

1. In a card-display cabinet, a main compartment having front, rear and side walls, a transverse partition and a plurality of longitudinal partitions dividing said main compartment into a plurality of card compartments, said transverse partition and said rear wall being provided with a plurality of finger openings, posts in said compartments adapted to engage recesses in the cards, and a handle strip adjacent said transverse partition and engaging a plurality of said posts.
2. In a display cabinet, a main compartment having front, rear and side walls, a transverse partition and a plurality of longitudinal partitions dividing said main compartment into a plurality of card compartments, said transverse partition and said rear wall being provided with a plurality of finger openings, and a handle strip extending over said transverse partition, said handle strip being provided along its front side with spaced finger recesses, each recess being aligned with the compartment therebelow.

3. In a card display cabinet having front, rear and side walls, a transverse partition forming two main compartments, each of said compartments having spaced apart and substantially parallel bottom walls, the bottom walls being upwardly and rearwardly inclined, a plurality of longitudinal partitions dividing said main compartments into a plurality of card compartments, a card retaining transverse strip secured to said cabinet and extending over said transverse partition, and a second card retaining strip secured to the front of said cabinet and extending over the front card compartments.

4. In a card display cabinet equipped with front, rear and side walls and a transverse partition forming two main compartments, a bottom wall having its front adjacent the bottom of said front cabinet wall and its rear end secured to the transverse partition at an intermediate point on said partition, a bottom wall for the rear main compartment having its front end adjacent the bottom of said partition and its rear end secured to the rear cabinet wall at an intermediate point on said wall, a plurality of longitudinal strips dividing said main compartments into a plurality of card compartments, and card retaining strips extending over the front portions of said card compartments.

EDWARD D. DAVIS.
